US0D1028972S

(12) **United States Design Patent** (10) **Patent No.:** **US D1,028,972 S**
(45) **Date of Patent:** **** May 28, 2024**

(54) **NOTEBOOK**

- (71) Applicant: **Samsung Electronics Co., Ltd.**, Suwon-si (KR)
- (72) Inventors: **Dongseok Lee**, Suwon-si (KR); **Iksang Kim**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/840,125**
- (22) Filed: **May 26, 2022**

Related U.S. Application Data

- (62) Division of application No. 29/680,813, filed on Feb. 20, 2019, now Pat. No. Des. 969,797.

(57) **CLAIM**

The ornamental design for a notebook, as shown and described.

DESCRIPTION

FIG. 1 is a top perspective view of a notebook, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged view of the encircled portion 9 in FIG. 2;

FIG. 10 is an enlarged view of the encircled portion 10 in FIG. 2;

FIG. 11 is an enlarged view of the encircled portion 11 in FIG. 4; and,

FIG. 12 is an enlarged view of the encircled portion 12 in FIG. 4.

The broken lines shown in the drawings depict portions of the notebook that form no part of the claimed design. The dot-dash broken lines in the drawings encircle portions of the claimed design that are illustrated in enlargements and form no part of the claimed design.

1 Claim, 6 Drawing Sheets
